UNITED STATES PATENT OFFICE.

GARFIELD A. WOOD, OF DETROIT, MICHIGAN.

TRUCK-BODY-DUMPING MECHANISM.

1,271,974.

Specification of Letters Patent.

Patented July 9, 1918.

Application filed January 15, 1917. Serial No. 142,404.

To all whom it may concern:

Be it known that I, GARFIELD A. Wood, a citizen of the United States, and residing at Detroit, in the county of Wayne and State of Michigan, have invented a new and Improved Truck - Body - Dumping Mechanism, of which the following is a specification.

It is common practice to dump the contents of truck bodies by lifting the front end upwardly about pivots near the rear end of the chassis by means of hydraulic hoisting means. A convenient source from which to operate the hoisting means is the propeller shaft, but, on account of the fact that the heavy loads and shocks incident to hoisting are borne on the side frames and independently of the propeller shaft, the deflection of the former is not transmitted to the latter. Again, it is desirable to provide for slight inaccuracies in the construction of either hoist or chassis (often made by different manufacturers), whereby assembling of the parts is facilitated. It is further desirable to avoid the liability to leakage which results from independently supporting the pumping and hoisting elements of which the hoisting means as a whole is made up. It is also especially desirable to so mount the pump and the connections whereby it is driven that they are least affected by dirt, that they occupy the least possible space and are least liable to interfere with operating rods and the like in the various chassis to which the hoisting means must be applied, in other words, to make a given embodiment of the invention as nearly as possible of general application. With these ends in view the present invention consists in a supplemental frame or support which extends across between the side bars of the chassis at about the upper level thereof, said supplemental frame depending, on one side only of the propeller shaft and supporting a pump and mechanism, including an endless member and clutch gear, whereby said pump is driven. The invention also consists in a supporting member depending upon one side only of the propeller shaft, together with a clutch gear bearing mounted solely upon said member and encircling the shaft and a clutch gear in said bearing, said gear being spaced from the shaft, whereby the pump may be driven regardless of deflection of the supporting member and without inducing bending stresses in the shaft.

The invention further consists in improvements in the clutch operating mechanism whereby the device is rendered more compact and less expensive; also in means whereby rattling of the clutch parts is prevented; also in means whereby the clutch parts are prevented from becoming accidentally disengaged while running. The invention further consists in the details of construction shown, described and claimed.

Certain general combinations of elements and certain specific features relevant to the construction of the mechanism shown and claimed herein are claimed in my earlier co-pending applications for U. S. Letters Patent, namely:

S. N. 183,979, filed August 1, 1917 (renewal of S. N. 14,480, filed March 15, 1915) and the division thereof S. N. 115,957, filed August 21, 1916;

S. N. 14,479, filed March 15, 1915, and the division thereof S. N. 117,235, filed August 28, 1916;

S. N. 117,236, filed August 28, 1916, 80
S. N. 185,797, filed December 8, 1916 and
S. N. 188,762, filed December 26, 1916.

In the drawings, wherein a preferred embodiment of the invention is shown, Figure 1 is fragmentary side elevation, parts being broken away. Fig. 1^a is a continuation of Fig. 1. Fig. 2 is a section looking rearwardly from a plane just back of the seat. Fig. 3 is an enlarged fragmentary plan view on the line 3—3 of Fig. 2, the pipes being removed. Fig. 4 is an elevation, parts being broken away, looking from the bottom in Fig. 3. Figs. 5 and 6 are sections on the lines 5—5 and 6—6, respectively, of Figs. 3 and 4. Fig. 7 is a fragmentary view from the top in Fig. 3.

1 indicates the side bars of the vehicle near the rear end of which are secured brackets bearing horizontal pivots 2 about which the body 3 may be swung vertically 100 for dumping. The front end of the body rests, when in lowered position, either directly on the side bars or on suitable chairs. This general construction is well known.

Extending transversely across the side bars at a point just forward of the front end of the body is a supplementary frame 4 upon which rests the flanged base 5 of a hydraulic (oil) hoisting cylinder 6 in which the piston rod 8 and associated piston are 110 reciprocable. By means of the cross-arm 9 which may swing about a pivot 10, the pul-

ley blocks 11, cables 12 (one end of each of which is preferably anchored to the supplementary frame), and the body arms 13 to which the other ends of the cables are attached, the piston may be utilized to tilt the body. It will, however, be understood that the construction thus far described may be widely varied. The usual longitudinally extending propeller shaft appears at 15, the suction pipe (which communicates with the upper end of the cylinder) at 16 and the delivery pipe (which communicates with the lower end of the cylinder) at 18.

The supplemental frame 4 includes a member 20, preferably an angle-iron, which depends at one side of the propeller shaft only and to a level somewhat below the latter—a portion of the lower end of the transverse flange of this member may be sheared away (Figs. 2 and 4) to receive the gear pump casing 21 that may be rigidly secured to the other (or longitudinally extending) flange by screw bolts 22 which are threaded in bosses 23 on the casing. The longitudinal flange of the member 20 is also perforated to receive screw bolts 24 (Fig. 3) whereby a bearing 25 (including the cap 26 and retaining screws 27) for the sprocket gear 28 is supported. The sprocket gear 28 has flanges 29 and 30 by which it is prevented from slipping longitudinally through the bearing, and it will be noted surrounds and is spaced considerably from the propeller shaft. To the latter is secured a split clutch member support 32 (the sections of which are united by the clamping bolts 33) and in this support a clutch member 34, which includes studs 35 journal d in ears 36 on the member 32, is mounted. The member 34 also includes spaced contact-elements 38 at substantially right angles to the axis of the studs 35, and these elements are notched as indicated at 39 to receive the curved heads 40 of the oppositely disposed clutch pins 41 which are slidable in the sprocket wheel 28. At their rear ends the clutch pins are slightly reduced and pass through the spool-shaped member 44, that is also spaced from the propeller shaft and has the central peripheral groove 45 in which is received contacts or shoes 46. Nuts 48 hold the pins 41 rigid with the member 44. The shoes 46 are pivotally mounted in the ends 48 of a divided clutch shifting member which includes a shank 49 having a rounded end 50 received in a socket in the face of the gear casing. It will be observed that the end 50 has considerable play in the socket, which relieves the shoes 46 from wear as the shaft 15 shifts back and forth slightly. The clutch shifting member is notched or grooved at 51 near the base of the yoke to receive the slotted bell crank 52 (pivoted upon one of the screw bolts 22) that may be actuated by the link 53 and

hand lever 54 mounted on the expansion chamber or other convenient location within reach of the seat 55 (Figs. 1 and 2.) It will be seen that the mounting of the end 50 of the yoke in the socket in the manner shown in Figs. 3 and 4 allows the shiftable clutch element a slight freedom of movement longitudinally of the shaft. A proper engagement of the heads 40 with the seats 39 may thus always be secured regardless of such longitudinally displacement as ordinarily takes place in the shaft 15 on account of wear, inertia, temperature or inaccuracy of construction.

A chain 56 (Fig. 2) connects the sprocket gear 28 to the sprocket gear 57 (Fig. 3) on the shaft 58 of the driving gear of the pump, and a suitable valve located within the casting and controlled by the arm 59, link 60 and hand lever 61 (also mounted within reach of the driver) completes the installation.

For the purpose of preventing the member 34 from rattling in the member 32 when the pins 41 are withdrawn, the outer ends of the studs 35 may be slotted or grooved to receive the end portions 63 of wire springs, the opposite ends of which are received in slots formed in the outer surfaces of the members 32 and retained in position by peening the metal down into the slot. The manner of securing the springs in position is, of course, merely illustrative.

Operation: The hand lever 54 is normally retained in a notch in the lug 65 but in case it should be jarred loose it will be noticed that the weight of the link 53 is applied to the crank 52 in such manner as to hold the clutch pins 41 withdrawn out of the path of the member 34; consequently there is no tendency for the pins to move to pump-driving position as the vehicle travels along the roadway. Again, when the clutch pins are purposely thrust to pump driving position the ribs 40 seat themselves in the corresponding grooves 39 (the propeller shaft may be running either clockwise or counter-clockwise, depending upon the particular engine or transmission used) and are thereby prevented from jarring loose, although the slight movement of the shaft forward and back which ordinarily takes place is allowed. This construction allows the supplemental frame to sink relatively to the propeller shaft (as is caused by the lifting of heavy loads) without impairing the driving connection and without inducing bending stresses in the shaft. Lack of alignment of the shaft 15 and gear 28 in one direction is compensated for by a pivotal movement of the member 34 about the axis of the studs 35; lack of alignment in a direction at right angles to the first named direction is compensated for by a relative movement of the ribs 40 and grooves 39.

The yoke member 48-49 of course swings about a vertical axis through the seat 50 when actuated by the crank 52.

The entire construction is very simple and 5 compact and readily adapts itself to the various makes of chassis; in case that side 10 of the chassis in which the pump and associated elements are located in Fig. 2 is obstructed by rods or the like, it is a simple 15 matter to reverse the necessary parts (that is, to make the parts "lefts," those shown being "rights") and mount the pump on the opposite side of the propeller shaft. The details of the construction may be 20 changed within wide limits without departing from the spirit of the invention, and I do not, therefore, wish to be limited except as indicated in the subjoined claims.

I claim:

- 20 1. In combination with the side bars and the longitudinally extending propeller shaft of a motor vehicle, a supplemental support extending across between the side bars and depending on one side only of said shaft, a 25 hoisting cylinder on the supplemental support, a pump for the hoisting cylinder and a pump driving gear supported on the depending portion of the supplemental support, said gear being hollow and of appre- 30 ciably greater internal diameter than the external diameter of the shaft, said shaft passing through the gear, whereby the supplemental frame may be deflected without inducing bending stresses in the shaft, and 35 means for driving said gear from the shaft at will.
2. In combination with the side bars and the longitudinally extending shaft of a motor vehicle, a supplemental support extending 40 across between the side bars and depending on one side only of said shaft, a hoisting cylinder on the supplemental support, a pump for the hoisting cylinder, a pump driving gear supported on the de- 45 pending portion of the supplemental support, said gear being hollow and of appre- ciably greater internal diameter than the external diameter of the shaft, said shaft passing through the gear, whereby the sup- 50 plemental frame may be deflected without inducing bending stresses in the shaft, and means for driving said gear from the shaft at will.
3. In combination with the frame and a 55 driven shaft of a motor vehicle, said frame and shaft constituting two members, a clutch element supported by one of said members and slidably longitudinally of the shaft, and a second clutch element supported by the 60 other member and tilttable about an axis at substantially right angles to the axis of the shaft, the engaging surfaces of said elements being shaped to prevent relative movement of said elements along the axis of the shaft.
- 65 4. In combination, a driven shaft, a clutch

member supported thereon, a second clutch member supported independently of said shaft and slidably longitudinally thereof, an element carried by the first clutch member and tilttable about an axis substantially intersecting the axis of the shaft and at substantially right angles thereto, said element having driving engagement with the second clutch member when the latter is in one position, and resilient means tending to hold the 75 tilttable element in a predetermined angular position in reference to its movement about its axis.

5. In combination, a driven shaft, a clutch member supported thereon a second clutch 80 member spaced from and surrounding said shaft and supported independently thereof, one of said members being slidable along the shaft, an element carried by one of the members and tilttable about an axis substantially 85 intersecting that of the shaft and substantially at right angles thereto, said element engaging the member other than that by which it is carried when the slidable member is in one position and being out of the path 90 thereof when the slidable member is in another position, the engaging surfaces of the element and the member other than that by which the element is carried being shaped to prevent disengagement from one another by 95 a movement parallel to the axis of the shaft.

6. In combination with the side bars and the longitudinally extending propeller shaft of a motor vehicle, a supplementary support 100 extending across between the side bars and depending on one side only of said shaft, a pump casing located on the side of the depending portion most remote from said shaft, a bearing located on the side of said depending portion nearest said shaft, a pump 105 driving gear mounted in said bearing, and means for driving said gear from said shaft at will.

7. In combination with the side bars and the longitudinally extending propeller shaft 110 of a motor vehicle, a supplementary support extending across between the side bars and depending on one side only of said shaft, a pump casing located on the side of the depending portion most remote from said shaft, a bearing located on the side of said depending portion nearest said shaft, a hollow pump driving gear mounted in said bearing, said gear surrounding said shaft and being spaced therefrom, and means for driving 115 said gear from said shaft at will.

8. In combination with the side bars and the longitudinally extending propeller shaft of a motor vehicle, a supplemental support 120 extending across between the side bars and depending on one side only of the shaft, a pump, a pump driving gear carried solely by the depending portion of the supplemental support, means for driving said gear from the shaft at will, and means for con- 125

- trolling the last mentioned means so arranged that the weight of the parts tends to hold said means out of pump driving relation.
- 5 9. In combination with the side bars and the longitudinally extending propeller shaft of a motor vehicle, a supplemental support extending across between the side bars and depending on one side only of the shaft, a
- 10 pump, a clutch member carried by the shaft, a other clutch member carried by the depending portion of the supplemental support and arranged to be driven from the first named clutch member, means for driving the
- 15 pump from the second named clutch member, and means including a member carried by said depending portion of the support and swingable about a vertical axis for controlling the second named clutch member.
- 20 10. In combination with the side bars and the longitudinally extending propeller shaft of a motor vehicle, a supplemental support extending across between the side bars, a pump, a pump driving gear carried by said
- 25 supplemental support, said gear encircling the shaft and being spaced therefrom, a clutch member carried by the shaft, another clutch member carried by the gear, and means including a member carried by said
- 30 supplemental support and swingable about a vertical axis for moving said second clutch member into engagement with the first named clutch member at will.
11. In a motor vehicle, a shaft, a clutch element carried thereby, a second clutch element surrounding the shaft and spaced therefrom and including means movable along the shaft into and from engagement with the first mentioned clutch element, a
- 35 member coöperating with the second clutch element to permit rotation thereof and to shift the movable means in either direction at will, and supporting means for said member constructed and arranged to permit universal swinging movement thereof.
- 40 12. In combination a shaft, a clutch ring surrounding the shaft and spaced therefrom, means for supporting the clutch ring to swing about an axis which is at substantially right angles to and substantially intersects the axis of the shaft, a tubular clutch element surrounding the shaft and spaced therefrom, pins mounted on said element to slide toward and from the clutch ring, said pins having
- 45 enlarged ends and the clutch ring having depressions therein at points considerably removed angularly from the axis about which it swings in which the enlarged ends of the pins are received.
- 50 13. In combination with side bars and a substantially horizontal driven shaft of a vehicle, a body pivoted to tilt in respect to said side bars, a supplementary support extending across between the side bars, a pump
- 55 and a hydraulic cylinder mounted on said support for tilting said body, means for driving said pump from said shaft, said means including a clutch element mounted on the supplementary support and slideable longitudinally of the shaft, and a second clutch element mounted on the shaft and tilttable about an axis at right angles to the axis of said shaft, the engaging surfaces of said elements being shaped to prevent movement of the second clutch element longitudinally of the shaft when power is being transmitted to the pump.
- 60 14. In combination with the side bars and a substantially horizontal driven shaft of a vehicle, a body pivoted to tilt in respect to said side bars, a supplementary support extending across between the said bars, a pump and a hydraulic cylinder mounted on said support for tilting said body, means for driving said pump from said shaft, said means including a clutch element mounted on the supplementary support and slideable longitudinally of the shaft, a second clutch element mounted on the shaft and tilttable about an axis at right angles to the axis of said shaft, the engaging surfaces of said elements being shaped to prevent movement of the second clutch element longitudinally of the shaft when power is being transmitted to the pump, and resilient means tending to prevent the second clutch element from vibrating about the axis at right angles to the shaft.
- 65 15. In combination with the frame of a vehicle and a tilttable body and a driven shaft supported thereon, a pump supported by said frame, means for driving the pump from the shaft, said means including a clutch element mounted on the frame and slideable longitudinally of the shaft, said clutch element encircling the shaft and being spaced therefrom, and a second clutch element mounted on the shaft and tilttable about an axis at right angles thereto, the first mentioned clutch element being arranged to engage the second clutch element in a plane at substantially right angles to the axis about which the second clutch element is tilttable, the engaging surfaces of said clutch elements being shaped to prevent movement of the second clutch element longitudinally of the shaft when power is being transmitted to the pump.
- 70 16. In combination with the side bars and the longitudinally extending propeller shaft of a motor vehicle, a supplementary support extending across between the side bars, said support depending between the side bars and including a thin plate at about the level of the propeller shaft, said plate being arranged in a longitudinal plane of the vehicle, a pump supported by the plate, said plate being interposed between the shaft and the pump, and means for driving the pump from the shaft at will.

17. In combination with the frame and a substantially horizontal driven shaft of a vehicle, a clutch element support carried by the frame, a clutch element supported by the frame and slidably longitudinally of the shaft, and a second clutch element mounted on the shaft and tilttable about an axis at right angles to the axis of the shaft, the engaging surfaces of said elements being shaped 5 to prevent relative movement of said elements along the axis of the shaft.
18. In combination with the frame and the longitudinally extending propeller shaft of a motor vehicle, a first clutch member carried by the shaft, a second clutch member coöperative with the first clutch member and slidably longitudinally of the shaft, said clutch members having inter-engaging surfaces shaped to prevent disengagement of 10 said members by a relative movement longitudinally of the shaft only, means for sliding the second clutch member, said means being constructed and arranged to allow limited free sliding movement of the second 15 clutch member, whereby the shaft may shift slightly longitudinally of its own axis at all times.
19. In combination with the side bars and a driven shaft of a motor vehicle, a supplementary support having a portion arranged substantially in a vertical longitudinal plane of the vehicle, a clutch member fixed to the shaft, a second clutch element carried by the support, yoke means swingable about a vertical axis and constituting a lever of the second class for shifting the second clutch member to and from engagement with the first clutch member, and a lever swingable about a horizontal axis and located along 20 the above mentioned portion of the support and engaging the yoke means between the ends thereof for swinging the clutch shifting means.
20. In combination with the frame and a driven shaft of a motor vehicle, a pump arranged substantially in the same horizontal plane as the shaft, the pump having a socket, a pump support carried by the frame, means for driving the pump from the shaft, 25 said means including a clutch, a swingable clutch shifting member having an end received in the socket, and a lever for swinging the clutch shifting member.
21. In combination with the frame and a driven shaft of a motor vehicle, a pump arranged at substantially the same level as the shaft, a pump support carried by the frame and interposed between the pump and the shaft, a pump driving gear mounted on the 30 support and encircling the shaft, and means for connecting the gear to the shaft at will, said means including a clutch member carried by the shaft, a shiftable clutch member supported by the gear, a yoke swingable about a vertical axis for shifting the last mentioned clutch member, and means for supporting and operating the yoke so constructed and arranged that the yoke also has limited angular movement about a horizontal line.
22. In combination with the frame and a driven shaft of a motor vehicle, a pump adjacent the shaft, a pump support interposed between the pump and the shaft, a threaded member for securing the pump to the support, clutch means for connecting the pump to the shaft at will, said clutch means including a lever swingable about the threaded member.
23. In combination with the frame and a driven shaft of a motor vehicle, a pump adjacent the shaft, a pump support interposed between the pump and the shaft, clutch means for connecting the pump to the shaft at will, said clutch means including a clutch shifting yoke swingable about a vertical axis and a lever swingable about a horizontal axis, the lever being slotted and embracing the yoke.
24. In combination with the frame and a driven shaft of a motor vehicle, a pump adjacent the shaft, a pump support interposed between the pump and the shaft, clutch means for connecting the pump to the shaft at will, said clutch means including a swingable notched clutch shifting yoke and a swingable lever having a divided end portion the divisions of which are received in the notch.
25. In a motor vehicle, a driven shaft, a clutch member carried thereby, a rotatable gear, a shiftable clutch member carried by the gear, a yoke for shifting the last mentioned clutch member, a support for the yoke including a socket in which the end of the yoke is received and in which the yoke may have limited universal swinging movement.
26. In a motor vehicle, a driven shaft, a clutch member carried thereby, a rotatable gear, clutch pins supported by and slidably through the gear to and from engagement with the clutch member, the ends of the pins on the side of the gear most remote from the clutch member having reduced ends forming shoulders, said ends being threaded, a spool-like member through which said ends pass, and nuts for drawing the pins up against the spool-like member to cause the shoulders to bear thereon.

GARFIELD A. WOOD.
